UNITED STATES PATENT OFFICE.

AUGUST SCHIEPE, OF CHARLOTTENBURG, GERMANY, ASSIGNOR TO HUGO FRIEDMANN, OF CHARLOTTENBURG, GERMANY.

TYPE-CASTING MACHINE.

No. 891,637.

Specification of Letters Patent.

Patented June 23, 1908.

Application filed December 26, 1907. Serial No. 408,017.

To all whom it may concern:

Be it known that I, AUGUST SCHIEPE, a citizen of the Empire of Germany, residing in Charlottenburg, near Berlin, in said Empire, have invented certain new and useful Improvements in Type-Casting Machines, of which the following is a specification.

The object of this invention is to provide a new or improved casting machine preferably for the manufacture of single printing type, in which the casting molds are arranged in groups in the usual way upon a carrier, for example on the periphery of a revolving drum, and are then successively brought in front of the casting mouth of a melting pot by intermittently moving the carrier drum. After the fluid metal has been forced into the molds under the action of a casting pump, the mold carrier, for example the drum is moved through an angle of say 90°, after which the cast printing type are freed from the runner connecting their feet and are then, on a further rotation of the mold carrier through an angle of say 90°, ejected from the molds and automatically conveyed into the channels of a suitable type magazine.

There is shown in the accompanying drawing a portion of a construction of type casting machine embodying this invention and in which the type molds of one font are arranged in four casting sections on the periphery of a wheel or drum which is rotated intermittently, each movement being through an angle of 90°.

The type molds successively pass in front of the casting hopper of an ordinary melting apparatus, in which position they are forced full of metal by the action of an ordinary casting pump. In the succeeding positions of the intermittently rotated wheel the type are freed from their runners, automatically ejected from the casting sections and conveyed into the channels of the type magazine.

The channels of the type magazine correspond in their arrangement and number to the several groups of casting molds.

Figure 1 shows partly in section and partly in elevation one casting section and the type magazine with the operating devices for the various movements. Figs. 2 and 2^a are front-views of the parts seen in Fig. 1 but

without the magazine; Fig. 3 is a detail view hereinafter referred to.

In this class of machine the molds for the bodies of the type are constructed in a similar way to that shown in Fig. 2 of the accompanying drawings from which it will be seen that small plates *e* serve as side boundaries and the faces of other small plates *d* as lower boundaries of the mold, the whole casting mold being covered in at the top by a common cover. Now great difficulty obtains in so fixing the cover that it shuts off the several casting molds in an absolutely liquid tight manner from each other, as for such purpose it must be in contact with the faces of all the small plates *e*. The result is that there is always trouble with the fluid metal overflowing at the top whereby the several types are caused to stick together. or similar troubles arise. In the improved machine this disadvantage is obviated by forming the upper boundary surfaces of the several molds of a number of small plates *c* which accurately correspond in thickness to the bottom plates *d*.

The molds for the bodies of the types are therefore formed by three differently shaped small plates *c*, *d*, and *e* which are held, preferably in dove-tail grooves *c*¹ and *d*¹, in the casting section *b*. The small plates *c*, *d* and *e* may however be secured in other ways, for example by flat grooves or the like, but the mounting must be very exact and so that the small plates can move sidewise in their grooves but not upwardly or downwardly or forwardly or backwardly.

The matrix plate *o* bears against the back of the small plates *c*, *d*, *e*. This matrix plate consists of a strip of metal into which are sunk the molds for the heads of the type. The matrix plate *o* may be adjustably secured to the casting section *b* by adjusting screws *o*¹ and corresponding clamping screws, or in any other similar manner.

Each casting section comprises cross bars *n*, *n*¹, *n*², *n*³ which are secured together by screws *o*².

To enable type of different sizes to be cast in one machine the small plates *d* and *e* are carried in the bar *n* which can be adjusted vertically in a dove-tail or similar groove and secured after adjustment by means of clamp-

ing and tension screws *g*. This adjustability may however be effected in other ways say for example by making the whole lower part of the casting section adjustable.

5 The upper part *n*³ is so mounted that it can be pushed out in the direction of the arrow Fig. 1. In this upper part the small plates *c* are likewise so secured in a dove-tail or similar groove that they can move sideways but not upwardly or downwardly or 10 backwardly or forwardly.

At their rear ends the small plates *c* are each prolonged at *p* and below this prolongation formed with a nose *s*. The nose *s* gives 15 the cast type a small nick, the signature so called, near its lower end in the vicinity of the foot. Several such noses may be provided on each top plate *c* arranged say behind each other so as to give to the type when 20 cast a number of nicks, or signatures. This is for the purpose of more exactly guiding the type bodies when sliding out.

When the upper part *n*³ is moved in the direction of the arrow the cast type will be 25 ejected from the section by the noses *s*. The upper part *n*³ moves so far outwardly that the entire type is brought out of the reach of the plates *c*, *d*, *e* only the projection *p* being still between the plates *e* and by this means 30 insuring the plates *c* being smoothly guided back into position between the side boundary plates *e*.

The upper part *n*³ is caused to slide back by mechanism shown in Figs. 1 and 2 in the following way:—On each end of the part *n*³ of the casting section is fixed a guide pin *t* which of course moves with the casting section in a circular arc. Upon a shaft *u* is mounted a U-shaped lever *v* the thickened 40 upper part of which is formed with guide grooves *w*. The lever *v* is given a pendulum-like movement, through a roller cam *x* which is fixed upon the driving shaft, or in any other similar manner.

45 When the pins *t* are situated in the guide grooves *w* the lever *v* makes a movement to and fro once and thereby pulls the upper part *n*³ once in and out.

When the upper part *n*³ moves outward 50 the type are carried with it and immediately thrust into the channels of the magazine. These channels accord in their arrangement exactly with the several casting instruments, as hereinafter described.

55 As now the freshly cast type frequently adhere to the upper plates *c* and would be consequently carried back again into the casting section or give rise to other troubles some appliance must be provided which will 60 knock off the type at the proper moment. Figs. 1 and 2 show one constructional form of the knocking off appliance but the knocking off may be effected in any other appropriate manner. Upon the shaft *u* and between 65 the members of the forked arm of the

lever *v* is mounted a double lever *y*, the lower end *y*¹ of which is recessed to removably embrace the lever *v*. One arm of a bell crank lever *z* engages the upper end of the lever *y*. The bell crank lever *z* is pivotally mounted 70 at *z*¹ and operates a slide 1. When the lever *v* is moved the smaller double lever *y* is likewise caused to move and, by means of the bell crank lever *z* to move the slide 1 upwardly or downwardly. To the slide 1 is attached 75 a knocking off tongue 2 which firmly holds the withdrawn cast bodies on the rearward movement of the part *n*³ and they then pass into the magazine. A spring 3 brings the lever *y* back into its normal position 80 after the conclusion of this operation. In order to prevent the casting sections from striking against the knocking off tongue 2 during the further movement of the former, arms 4 are fixed to the slide 1 which, during 85 the angular movement of the casting sections, are forced back by the next following casting section and consequently moves the knocking off tongue 2 out of the range of the rotating casting drum. This operation is repeated 90 in like manner on each rotation of the drum through an angle of 90°.

In order that the knocking off appliance shall work properly it is necessary to stop the casting drum exactly at the proper time; a 95 constructional example of an appliance for this purpose is shown in Fig. 3. 5 is a lever that is moved from the driving shaft by a suitable cam 6. It is pivoted at 7 and its upper end carries a bolt 8 which at the proper 100 moment engages periodically in each of the four holes of an arresting disk 9 and releases it again also at the proper moment, after which the arresting disk is again permitted to rotate through an angle of 90°.

105 It has been found in practice that in the working of such casting machines the plates *c*, *d* and *e* must be very tightly pressed together at the moment of casting so as to prevent any metal flowing between them or overflowing from the molds formed by the plates which prevention is necessary in order to obtain sharp edged type bodies. For this purpose, according to this invention there is provided an appliance of very simple 110 construction and the action of which is certain. On each side of the casting section is arranged a pressure lever *f*, Figs. 1 and 2, which is pivoted at *g* by means of a screw 115 threaded bolt *h* which has preferably a screw 120 thread of rapid pitch. Projecting from the lever *v* in the path of the casting section, at suitable points such as *i*, are pins *k* which, at the proper moment, come into contact with the pressure levers *f* and rotate them to a certain extent and then leave them again by 125 passing through a groove *l* formed therein. This rotation of the lever *f* and consequently also that of the screw threaded bolt *h* presses the plates *c*, *d* and *e* still more closely to- 130

gether than they were already pressed together by the hand adjusted set screws *m*. This operation is repeated at each partial rotation of the drum *a* through an angle 5 of 90°.

Before the type bodies enter the magazine the runners still adhering thereto are removed by a suitable appliance shown in Fig. 2. This appliance consists of a cutter disk 10 which is rotated through suitable gearing 11 and is moved to and fro by a series of rods 12. Grooves 13 or the like guide the cutting appliance in the frame of the machine. Two rollers 14 adapted to run over the face 15 of the casting section carry the appliance and so guide it as to insure that the same amount is always cut away. The cutting arrangement is regulated by an adjustable screw threaded bolt 16 having threaded on 20 it a spring 17 which constantly tends to force the running rollers downwardly.

A further improvement, that facilitates the proper working of the machine is the provision of a device for previously heating 25 up the several casting sections; such device consists for example of a gas pipe 18 as shown in Figs. 1 and 2.

Upon the casting machine is also provided a movable magazine bridge adapted to receive in four channels formed by separate 30 rulers, the type when finished and ejected from the machine by the ejecting appliance hereinbefore described. The swinging magazine bridge is driven by a four stepped cam 35 or the like 19 keyed upon the drum shaft 20. The entire magazine 25 is carried by a standard 23 in a bearing 26. Upon the standard 23 is pivoted one end of a lever arm 21 whose other end carries a lateral pin 22 on which is 40 mounted to rotate a roller that works upon the cam 19. The cam is intermittently rotated through an angle of 90°. As the cam 19 is constructed as a four step cam the lever arm 21 will be moved into four different 45 positions which will be transmitted to the swinging magazine bridge 25 by the link 24. The steps of the cam 19 correspond in their 50 distances from the center exactly to the distances apart of the several compartments of the magazine thereby insuring that the casting section provided with finished printing type comes in line with a corresponding compartment of the magazine at every partial rotation through an angle of 90° of the cam. 55 The finished printing type are therefore ejected out of the casting section by the appliance already described and pass into the channels of the magazine bridge formed by rulers, where one type ranges itself against 60 the other and pushes it further on, as well understood.

What I claim is:—

1. In a type casting machine, a rotary carrier, groups of molds on said carrier comprising plates that form the bottoms and sides of

said molds and upper plates adapted to form the tops of said molds, means for intermittently rotating said carrier in steps that bring said groups of molds successively into position for casting type, a member for each group of molds in which the upper plates of said molds are mounted, and means adapted to move said member with said upper plates forwardly and backwardly at each intermittent movement of said carrier. 70

2. In a type casting machine, a rotary carrier, groups of molds on said carrier comprising plates that form the bottoms and sides of said molds and upper plates adapted to form the tops of said molds, downwardly extending projections on the lower side of the upper plates of said molds adapted to nick type when being ejected from said molds, means for intermittently rotating said carrier in steps that bring said groups of molds successively into position for casting type, a member for each group of molds in which the upper plates of said molds are mounted, and means adapted to move said member with said upper plates forwardly and backwardly 85 at each intermittent movement of said carrier. 90

3. In a type casting machine, a rotary carrier, groups of molds on said carrier comprising plates that form the bottoms and sides of 95 said molds and upper plates adapted to form the tops of said molds, downwardly extending projections on the lower side of the upper plates of said molds arranged to slide between the side plates of said molds to guide 100 said upper plates and adapted to nick type when being ejected from said molds, means for intermittently rotating said carrier in steps that bring said groups of molds successively into position for casting type, a member 105 for each group of molds in which the upper plates of said molds are mounted, and means adapted to move said member with said upper plates forwardly and backwardly at each intermittent movement of said carrier. 110

4. In a type casting machine, a rotary carrier, groups of molds on said carrier comprising plates that form the bottoms and sides of said molds and upper plates adapted to 115 form the tops of said molds, means for intermittently rotating said carrier in steps that bring said groups of molds successively into position for casting type, a member for each group of molds in which the upper plates of 120 said molds are mounted, means adapted to press the molds of said groups of molds together at the time of casting, and means adapted to move said member with said upper plates forwardly and backwardly at each 125 intermittent movement of said carrier.

5. In a type casting machine, a rotary carrier, groups of molds on said carrier comprising plates that form the bottoms and sides of said molds and upper plates adapted to form 130

the tops of said molds, means for intermittently rotating said carrier in steps that bring said groups of molds successively into position for casting type, a member for each 5 group of molds in which the upper plates of said molds are mounted, means adapted to press the molds of said groups of molds together at the time of casting, means for cutting the feet of type cast in said molds while 10 said pressing means are in operation, and means adapted to move said member with said upper plates forwardly and backwardly at each intermittent movement of said carrier.

15 6. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into position for casting type, a member for each 20 group of molds in which the upper plates of said molds are mounted, tightening screws adapted to press the molds of said group of molds together, levers on said tightening screws, projections in the path of said levers adapted to rock said levers to turn said screws in a direction to press said molds together before the operation of casting, and means adapted to move said member with said upper plates forwardly and backwardly at each intermittent movement of said carrier.

35 7. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into position for casting type, a member for each 40 group of molds in which the upper plates of said molds are mounted, a lever formed with guide grooves near one end, a pivot for said lever fixed relatively to said carrier, means for rocking said lever about said pivot, pins on said members adapted to enter and engage the guide grooves of said lever, a plate adapted to strike type ejected from said molds, a bell crank lever to one arm of which 45 said plate is pivoted, a spring pressed pivoted lever one arm of which engages the other arm of said bell crank lever, and a part of said grooved lever engaging said spring pressed lever.

50 8. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into position for casting type, a member for each 55 group of molds in which the upper plates of said molds are mounted, means adapted to move said member with said upper plates forwardly and backwardly at each intermittent movement of said carrier, and means adapted to strike type ejected from said molds.

60 65 9. In a type casting machine, a rotary car-

rier, groups of molds on said carrier comprising plates that form the bottoms and sides of said molds and upper plates adapted to form the tops of said molds, means for intermittently rotating said carrier in steps that bring said groups of molds successively into position for casting type, a member for each 70 group of molds in which the upper plates of said molds are mounted, means adapted to move said member with said upper plates 75 forwardly and backwardly at each intermittent movement of said carrier, a plate adapted to strike type ejected from said molds, a bell crank lever to one arm of which said plate is pivoted, a spring pressed pivoted lever one arm of which engages the other arm of said bell crank lever, and means adapted to rock said spring pressed lever.

10 10. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into 80 position for casting type, a member for each group of molds in which the upper plates of said molds are mounted, a lever formed with guide grooves near one end, a pivot for said lever fixed relatively to said carrier, means for rocking said lever about said pivot, pins on said members adapted to enter and engage the guide grooves of said lever, a plate adapted to strike type ejected from said molds, a bell crank lever to one arm of which 85 said plate is pivoted, a spring pressed pivoted lever one arm of which engages the other arm of said bell crank lever, and a part of said grooved lever engaging said spring pressed lever.

105 11. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into 110 position for casting type, a member for each group of molds in which the upper plates of said molds are mounted, means adapted to move said member with said upper plates forwardly and backwardly at each intermittent movement of said carrier, and means for holding said carrier when said group of molds are in position for casting.

115 12. In a type casting machine, a rotary carrier, groups of molds on said carrier comprising plates that form the bottoms and sides of said molds and upper plates adapted to form the tops of said molds, means for intermittently rotating said carrier in steps that bring said groups of molds successively into 120 position for casting type, a member for each group of molds in which the upper plates of said molds are mounted, means adapted to 125

move said member with said upper plates forwardly and backwardly at each intermittent movement of said carrier, a disk on said carrier formed with holes, a fixed part formed 5 with a hole in line with which the holes of said disk are successively brought by movement of said carrier, a pin working through the hole of said fixed part and adapted to enter the holes of said disk, a lever to which 10 said pin is pivoted, and a rotary cam for actuating said lever.

13. In a type casting machine, a rotary carrier, groups of molds on said carrier comprising plates that form the bottoms and 15 sides of said molds and upper plates adapted to form the tops of said molds, means for intermittently rotating said carrier in steps that bring said groups of molds successively into position for casting type, a member for 20 each group of molds in which the upper plates of said molds are mounted, means adapted to move said member with said upper plates forwardly and backwardly at each intermittent movement of said carrier, and means 25 adapted to remove casting runners from type cast in said molds.

14. In a type casting machine, a rotary carrier, groups of molds on said carrier comprising plates that form the bottoms and 30 sides of said molds and upper plates adapted to form the top of said molds, means for intermittently rotating said carrier in steps that bring said groups of molds successively into position for casting type, a member for 35 each group of molds in which the upper plates of said molds are mounted, means adapted to move said member with said upper plates forwardly and backwardly at each intermittent movement of said carrier, a rotary cutting 40 tool adapted to remove casting runners from type cast in said molds, means for rotating said tool, means adapted to press said tool towards type to be cut and means adapted to reciprocate said tool in the path of the type.

45 15. In a type casting machine, a rotary carrier, groups of molds on said carrier comprising plates that form the bottoms and sides of said molds, and upper plates adapted to form the tops of said molds, means for 50 intermittently rotating said carrier in steps that bring said groups of molds successively into position for casting type, a member for each group of molds in which the upper plates of said molds are mounted, means 55 adapted to move said member with said upper plates forwardly and backwardly at each intermittent movement of said carrier, and means adapted to heat said molds prior to a casting operation.

60 16. In a type casting machine, a rotary carrier, groups of molds on said carrier comprising plates that form the bottoms and sides of said molds, and upper plates adapted to form the tops of said molds, means for 65 intermittently rotating said carrier in steps

that bring said groups of molds successively into position for casting type, a member for each group of molds in which the upper plates of said molds are mounted, means adapted to move said member with said upper plates forwardly and backwardly at each intermittent movement of said carrier, and a gas burner under the influence of whose flame the groups of molds are successively brought by said carrier.

75 17. In a type casting machine, a rotary carrier, groups of molds on said carrier comprising plates that form the bottoms and sides of said molds, and upper plates adapted to form the tops of said molds, means for 80 intermittently rotating said carrier in steps that bring said groups of molds successively into position for casting type, a member for each group of molds in which the upper plates of said molds are mounted, means adapted to move said member with said upper plates forwardly and backwardly at each intermittent movement of said carrier, a type magazine comprising compartments arranged one 85 above the other the type channels of each of which correspond in their arrangement with said molds, a fixed pivot on which said magazine is mounted, and means for intermittently moving said magazine about its pivot.

90 18. In a type casting machine, a rotary carrier, groups of molds on said carrier comprising plates that form the bottoms and sides of said molds, and upper plates adapted to form the tops of said molds, means for 95 intermittently rotating said carrier in steps 100 that bring said groups of molds successively into position for casting type, a member for each group of molds in which the upper plates of said molds are mounted, means adapted to move said member with said upper plates 105 forwardly and backwardly at each intermittent movement of said carrier, a type magazine comprising compartments arranged one above the other the type channels of each of which correspond in their arrangement with 110 said molds, a fixed pivot on which said magazine is mounted, and means for intermittently moving said magazine about its pivot to different extents dependent upon into which compartment of said magazine type 115 are to be delivered.

19. In a type casting machine, a rotary carrier, groups of molds on said carrier comprising plates that form the bottoms and sides of said molds and upper plates adapted 120 to form the tops of said molds, means for intermittently rotating said carrier in steps that bring said groups of molds successively into position for casting type, a member for each group of molds in which the upper plates 125 of said molds are mounted, means adapted to move said member with said upper plates forwardly and backwardly at each intermittent movement of said carrier, a type magazine comprising compartment arranged one 130

above the other the type channels of each of
which correspond in their arrangement with
said molds, a fixed pivot on which said maga-
zine is mounted, a step cam rotating with
5 said carrier, a lever, a fixed pivot on which
said lever is mounted, a roller on said lever
working on the steps of said cam, and a link
connecting said lever to said magazine.

In testimony, that I claim the foregoing as
my invention, I have signed my name in 10
presence of two subscribing witnesses.

AUGUST SCHIEPE.
